UNITED STATES PATENT OFFICE

ARTHUR B. BABBITT, OF KENT, OHIO

TAMPING MACHINE

Application filed June 5, 1928. Serial No. 282,901.

This invention relates to improvements in tamping machines, particularly machines for tamping concrete in forms for the production of concrete blocks.

5 In machines of this kind there are employed a series of vertically arranged, vertically movable tampers which are necessarily relatively heavy. These tampers are raised by a cam motion and are permitted 10 to descend in response to the action of gravity in order to perform the tamping operation. For the purpose of speeding up the work as much as possible, the movements of the cam are quite rapid, and as a consequence 15 of this fact and the weight of the tampers, considerable inertia is set up in each tamper as it moves upwardly which tends to carry the tampers upward further than is desirable. It is not practical to increase their 20 length to such an extent that gravity alone would terminate the upward movement because of the necessary increase in the size of the machine and because every increase in the length of the tamper bar increases its 25 weight and hence its inertia, to say nothing of the increased power required and the slowing up of the operation.

If the tampers are brought to a stop by being permitted to strike against some rigid 30 element upon the frame, the vibration is excessive with a consequent racking of the joints and movable parts, disintegration of the metal of the machine and loosening of attached parts, with a resulting short life 35 for the machine. Tamping machines have been built employing springs or rubber blocks to cushion and stop the upward movement of the tampers, but these machines have been unsatisfactory because the springs or blocks necessary to stop the upward 40 movement have given a strong impetus to the tampers at the beginning of their downward movement and this has been harmful to the latches which must be employed to 45 catch the tamper bars and hold them in re-

tracted position after a tamping operation has been completed and while the form is being removed and another placed in position in the machine.

One of the objects of the present invention, therefore, is the provision of a tamping machine in which the upward motion of the tampers may be brought to a stop easily and gradually so as not to impart a shock to the machine frame, with consequent vibration. 50

Another object is the stopping of the upward motion of the tampers without storing up energy that is immediately consumed in the downward motion of the tampers, in other words, so stopping the upward motion 60 as to leave the tampers free to move downwardly by gravity alone. 55

A further object is the provision of a tamper stopping means which will permit the use of heavy tampers and greater speeds of tamper movement than have been possible heretofore. 65

Still another object is the provision of a tamper stopping means which is capable of ready adjustment in order to compensate 70 for variations in weight or speed of movement of the tampers.

Other objects and features of novelty will appear as I proceed with the description of that embodiment of the invention which, for the purposes of the present application, I have illustrated in the accompanying drawings, in which: 75

Fig. 1 is a front elevational view of a tamping machine embodying my invention; 80

Fig. 2 is a transverse vertical sectional view taken substantially on the line 2-2 Fig. 1;

Fig. 3 is a horizontal sectional detail view 85 taken substantially on the line 3-3 Fig. 1, the parts being shown on a larger scale; and

Fig. 4 is a detail sectional view of a frictional retarder which may be employed in connection with the invention, the view be- 90

ing taken substantially on the line 4—4 Fig. 1.

In the drawings, the frame of the machine is shown as comprising a pair of side members 10 of angle bar form, with a cross bar 11 at the base and further cross bars 12 and 13 joining the side members above the base. Upon the cross bars 12 and 13 there is supported a supplemental frame which includes vertical members 14 and 15 and transverse or horizontal members 16 and 17. In this supplemental frame is mounted the bulk of the movable parts of the machine. These parts will be described with great attention to detail as a detailed description will be found in my patent No. 1,518,240, issued December 9, 1924, and as the present invention is applicable to all tamping machines of this general character.

In the supplemental frame is mounted an upper cast bar 18 and a lower cast bar 19 substantially identical in form, each of these bars being provided with sockets 20 having spherically curved lower portions within which are mounted bearing members 21 formed with complementary spherical lower surfaces and having also upper spherical surfaces engaged by plates 22 that are secured to the cast bars 18 or 19, as the case may be, by bolts 23. The members 21 are bored out to provide slide bearings for vertically movable tamper bars 24, the ball and socket mountings for these bearings, as above described, being adapted to automatically adjust themselves in alignment and thus insure free and easy movement of the bars 24 in their slide bearings. Each of the tamper bars 24 has a foot or shoe 25. The number of tampers may, of course, be varied to suit conditions.

Each of the tamper bars 24 has fixed thereupon a bracket 26 to which is pivoted a spring-pressed impact plate 27. The brackets 26 have arms 28 provided with openings fitting over rods 29 that are fixed in the angle bars 16 and 17 of the supplemental frame. By this latter means the bars 24 and the brackets 26 are prevented from turning. A cover plate 30 may be mounted upon the angle bars 16 and 17 if desired.

The tampers are raised one at a time by a series of arms 31 having rollers 32 on their extremities, each adapted to engage the impact plate 27 on one of the brackets 26. The spring mounting of the impact plates serves to cushion the blows delivered by the rollers 32 and lessens the noise of the same. These arms 31 are all mounted upon a shaft 33 which has bearing in the supplemental frame and is provided with a belt pulley 34 that is continuously driven from some suitable source of power.

In order to hold the tampers in elevated position where the impact plates 27 are out

of reach of the rollers 32, there are provided a series of latches 35 pivoted at their upper extremities on the bar 16. The hooks at the lower ends of these latches are adapted to engage beneath projections 36 on the brackets 26. Normally, the latches 35 are all retracted by means of a slide bar 37 having pins 38 for engagement with the latches, the bar 37 being movable by means of a bell crank lever 39 and an operating rod 40. When the operation of the tampers is to be interrupted, the rod 40 is moved to the position illustrated in Fig. 1, whereupon the latches swing down and catch the projections 36 after they have moved upwardly beyond the hooks of the latches which are cam-shaped on their lower sides for this purpose. When the rod 40 is pulled downwardly to again start the operation of the machine, the tampers all fall simultaneously until the feet 25 strike the concrete in the mold or until the brackets 26 engage coil springs 41 surrounding the tamper bars 24, when the impact plates 27 are in position to be engaged by the arms 31 and again raised one at a time.

The means which I employ for retarding the upward movement of the tamper bars will now be described. The upper ends of the side members 10 of the frame are slotted for a short distance down from the tops thereof, as shown at 42 in Fig. 2. A transverse bar 43 is arranged crosswise of the frame at the upper end thereof, resting upon blocks 44 secured to the side members 10. In cross-section, this bar is preferably an inverted T, and at its extremities the horizontal portions of the T are removed and the vertical web permitted to extend through the slots 42 with a loose sliding fit. As guiding and steadyng means in addition to the slots 42, I may secure a plate 44 to the rear flange of each side member 10 and a short piece of smaller size angle bar 45 to the inner flange of the member 10. To the bottom or horizontal portion of the bar 43 I may attach a cushioning element composed of two strips 46 of rubber belting or the like and a wear plate 47 of relatively thin sheet metal. While I do not regard this cushioning element as essential, it is advantageous particularly as a noise deadener.

Interposed between each end of the bar 43 and the adjacent side member 10 of the frame there is a frictional motion retarding means. The shock absorbers commonly used upon automobiles, wherein the rebound of the action of the springs is opposed by frictional contact between two relatively movable parts, are well suited to the purpose. One such device that I have employed with satisfactory results, known to the trade as a "snubber", is illustrated herein by way of example, being marked 49. It is supported

5 by means of a bracket 50 attached to the underside of bar 43. Referring to Fig. 4, 51 is a fixed tubular element in which is slidably mounted a short bar 52. There are shoes 53 and 54 on the remote extremities of the parts 51 and 52. A coil spring 55 tends to expand these parts 51 and 52. The inner ends of a metal band 56 and of a friction strap 57 are secured to the shoe 53. There are a number of convolutions of 10 this band and strap, and the outer end of the strap is continued downwardly and attached to the frame side member 10, as shown.

15 When a pull is exerted upon one of the straps 57, it unwinds somewhat, but in doing so the movement of its convolutions over each other is frictionally retarded. At the conclusion of such a movement, the 20 spring 55 immediately rewinds or takes up the slack in strap 57, and the device is set for the next motion retarding operation.

As the roller 32 on each arm 31 strikes the impact plate 27 of the corresponding 25 bracket 26, the tamping bar to which the bracket is attached is thrown upwardly quite violently and the upper end of the bar strikes a blow upon the transverse bar 43, which will be referred to hereinafter sometimes as a pad. This blow tends to raise 30 the pad and does so to some extent. The raising of the pad is opposed by the two snubbers 49, the retarding action of the snubbers being divided between the two 35 snubbers in a proportion which is affected by the distance of each snubber from the particular bar 24 which delivers the blow. For instance, the parts may be so designed and arranged that the upward motion of 40 either of the end bars 24 is opposed exclusively or almost exclusively by the adjacent snubber, the pad then rocking upwardly upon the block 44 at the opposite side of the frame as a fulcrum.

45 The movement of the bar 43 is quite small in practice, being about one-fourth of an inch in a machine of average size and speed employing small snubbers such as are commonly used upon automobiles, and the machine with this apparatus applied to it is surprisingly free from vibration. Furthermore, the wear and tear upon the latch mechanism is reduced to almost nothing as the upward motion of the bars 24 is terminated at a point just high enough to permit the latches to swing under the projections 36, that is, before gravity has had an opportunity to act upon the tampers long enough to impart any appreciable blow to 55 the latch hooks.

Having thus described my invention, I claim:

1. In a tamping machine, a frame, 60 tampers supported therein for vertical movement, means for imparting upward

impulses to said tampers, and means for frictionally retarding the upward movement of the tampers.

2. In a tamping machine, a frame, tampers supported therein for vertical movement, 70 means for imparting upward impulses to said tampers, and means becoming effective near the limit of upward movement for snubbing or braking said movement, said last-named means leaving the downward movement 75 unaffected.

3. In a tamping machine, a frame, tampers supported therein for vertical movement, means for imparting upward impulses to said tampers, and means for limiting the 80 extent of the upward movement of the tampers comprising devices arranged to frictionally retard upward movement and permit free downward movement.

4. In a tamping machine, a frame, tampers supported therein for vertical movement, means for imparting upward impulses to said tampers, and means for limiting the extent of the upward movement of the tampers comprising cooperating frictional surfaces 90 partaking of relative motion in contact with each other as the tampers move upwardly.

5. In a tamping machine, a frame, tampers supported therein for vertical movement, means for imparting upward impulses to 95 said tampers, means for limiting the extent of the upward movement of the tampers comprising a device arranged to frictionally retard upward movement, and a transverse bar connected to said device and movably supported in said frame in a position to be contacted by said tampers.

6. In a tamping machine, a frame, tampers comprising vertical bars arranged in alignment in said frame and slidably supported 105 therein, means for imparting upward impulses to said tampers one at a time, a transverse bar with which said tampers are adapted to engage near the desired upward limit of their motion, said bar being mounted 110 for slight vertical movement, and frictional retarding means acting between each end of said transverse bar and said frame, said means being adapted to retard the upward movement of said transverse bar.

7. In a tamping machine, a frame, tampers supported therein for vertical movement, means for imparting upward impulses to said tampers, a pad against which said tampers are adapted to strike at substantially the upward limit of their motion, means upon said frame upon which said pad is adapted to fulcrum, and means connecting a remote portion of the pad with the frame comprising a device arranged to frictionally 120 retard the upward tilting of the pad.

8. In a tamping machine, a frame, tampers supported therein for vertical movement, means for imparting upward impulses to said tampers, a pad against which said 130

tampers are adapted to strike at substantially the upward limit of their motion, oppositely arranged fulcrum points for said pad upon said frame, and means connecting said pad with said frame near each fulcrum point, said means comprising a device arranged to frictionally retard the upward movement of the pad.

In testimony whereof, I hereunto affix my
10 signature.

ARTHUR B. BABBITT.
